A. J. MARSCHALL.
COOLING APPARATUS FOR INTERNAL COMBUSTION ENGINES.
APPLICATION FILED JULY 5, 1918.

1,316,912.

Patented Sept. 23, 1919.

UNITED STATES PATENT OFFICE.

ADOLF J. MARSCHALL, OF MADISON, WISCONSIN.

COOLING APPARATUS FOR INTERNAL-COMBUSTION ENGINES.

1,316,912.

Specification of Letters Patent. Patented Sept. 23, 1919.

Application filed July 5, 1918. Serial No. 243,307.

To all whom it may concern:

Be it known that I, ADOLF J. MARSCHALL, a citizen of the United States, residing at Madison, in the county of Dane, State of Wisconsin, have invented certain new and useful Improvements in Cooling Apparatus for Internal-Combustion Engines; and I do hereby declare the following to be a full, clear, and exact description of the invention, such as will enable others skilled in the art to which it appertains to make and use the same.

This invention relates to cooling apparatus for internal combustion engines and has for its object to provide an efficient cooling system which will do away with the complication, inconvenience and frequent trouble unavoidable with the water circulating systems now almost universally employed in automobiles, aeroplanes, etc.

There are at present, as regards their cooling systems, two types of internal combustion engines on the market, known popularly as water-cooled and air-cooled engines. By far the greater number of engines, particularly automobile engines, are of the water-cooled type. In fact, so far as I am aware, there is on the market but one make of air-cooled automobile engine which has attained any substantial commercial success.

The common water-cooled system comprises essentially a jacket surrounding the portions of the cylinder walls which form the explosion chamber, a radiator of sufficient surface area to maintain the desired temperature of the water and a pump or other circulating device for maintaining the water in continuous circulation through the radiator and the jacket.

This apparatus involves practical difficulties in that the radiator due to the large surface required and the constricted space permissible on an automobile, is necessarily of more or less fragile construction and is therefore unavoidably subject to leakage and clogging. Also, the pump is liable to become clogged and its driving mechanism adds to the complication of the motor. Were the air cooling systems heretofore in use generally regarded as satisfactory, they would obviously replace the water cooling system, as these troublesome parts are done away with.

The chief difficulties of air cooling are the difficulty of obtaining sufficient radiating

surface without having an over-thickness of metal between the explosion chamber and the surface of the radiating projections, and the difficulty of maintaining a uniform circulation of air over the surface of the cylinders so as to utilize the entire surface efficiently and maintain the cylinder walls at an approximately uniform temperature throughout.

By my invention I provide a cooling system in which I have incorporated the advantages of both the water cooling and the air cooling system in that I avoid the pump and radiator of the water cooling system and at the same time provide a larger cooling surface and a uniform cooling of the cylinder walls, thereby correcting the defects of the air cooled motor.

In the accompanying drawings I have illustrated a preferred embodiment of the invention in its application to an internal combustion engine of a standard four-cylinder type, and in said drawings,

Fig. 1 is a side elevation of such an engine equipped with my invention with certain parts shown in section and broken away for convenience of illustration;

Fig. 2 is a transverse section through the engine shown in Fig. 1; and

Figs. 3 and 4 are diagrammatic representations of possible modifications of the structure of Figs. 1 and 2.

Referring to the drawings, 1 indicates the internal combustion motor, here shown in outline only and with its operating parts removed, the motor comprising four cylinders, 2, mounted vertically in a row on the crank case. Each cylinder comprises a piston 3, one of which is shown in its lowermost position to indicate the extent of the explosion chamber between the upper surface of the piston and the top of the cylinder, which is the portion of the engine that must be cooled for the engine to be continuously operated.

In carrying out my invention I surround the upper portion of the cylinders constituting the explosion chambers with a jacket 4 generally similar to the water jackets of ordinary water cooled motors, but preferably of larger capacity, particularly over the tops of the cylinders, as indicated in Fig. 1. The jacket may be cast integral with the cylinders in the usual manner of water jackets, or the lower part only may be cast integral

with the cylinders, the upper part 5 for all the cylinders being formed in a separate piece and attached to the lower part, as indicated at 6. The jacket is fluid-tight and is 5 normally filled or substantially filled with water or some other substance which is liquid at the operating temperatures of the engine. A vent or blow-off valve 19 is preferably provided at the top of the jacket to 10 relieve excessive pressure in case the substance in the jacket is heated above its boiling point.

To further increase the radiating capacity 15 of the jacket its outer surface is provided with fins or ribs 7, the ribs preferably extending vertically along the side walls of the casing and longitudinally across the top to provide passages through which the air will be drawn by a suitable exhaust fan, the 20 casing of which is indicated at 8. The exhaust fan is connected through a pipe 9 with an outer casing or cover 10 surrounding the jacket 4 and supported on the engine in any suitable manner, as for instance 25 by the brackets 11. The casing 10 is spaced from the ribs of the jacket to allow a large volume of air to be readily drawn through the casing by the action of the fan.

The casing 10 may be of any desired construction, but is preferably formed with its 30 upper portions hinged as indicated at 12 (Fig. 2) along the middle of the top to give ready access to the spark plugs, etc., of the motor inclosed therein.

35 The operation of my improved cooling system is as follows: The water or other liquid in the jacket 4 serves several purposes. In the first place, the water absorbs the heat from the cylinder walls much more rapidly 40 than air at the same temperature. In the second place, the water in circulation, due to its heating at the cylinder walls and cooling at the jacket walls, maintains a uniform temperature throughout, thereby obviating 45 uneven cooling and the consequent uneven expansion and contraction which is one of the chief faults of the air-cooled engine. Further, by the use of the water jacket, the ultimate cooling surface, that is, the ribbed 50 surface of the jacket, is much more extensive than can be had by forming the ribs directly on the face of the cylinders, as in air-cooled engines, for if the fins are unduly long, the path of conduction of the heat through the 55 metal is increased so that all the surface is not effective. As the water transmits the heat by convection and not by conduction, the distance of the jacket wall from the wall of the cylinder is immaterial and the jacket 60 wall will be so proportioned as to give an external surface sufficiently great for the air circulating system to provide the necessary heat absorbing capacity.

The uniform temperature of the liquid in 65 the jacket not only equalizes the heat absorp-

tion from the several cylinders, but also maintains the walls of the jacket at substantially uniform temperatures throughout, regardless of the greater circulation of air at some points than others.

I am aware that air cooled engines having 70 external radiating fins formed on the cylinders have been used in conjunction with inclosing casings having air exhaust fans or blowers for producing a forced circulation 75 of air around the cylinders. Such devices have not, however, been altogether satisfactory for the reason that it is difficult to construct the engine fins and casing in such manner as to maintain a uniform circulation 80 of air throughout all parts of the casing, the result of which is that portions of the cylinder walls are cooled, while at other portions the circulation is no better than if the forced draft apparatus were not used at all. This 85 uneven cooling not only produces an internal stress in the metal due to the uneven expansion and contraction, but the excessive heat in spots interferes with the lubrication, causing the cylinders to score, and otherwise 90 deranging the motor.

With my improvement this defect of the air circulating systems heretofore unavoidable is done away with because the temperature of the cylinder wall is determined solely 95 by the inclosed liquid, the temperature of which is substantially uniform as it is determined by the average radiating capacity of the jacket as a whole.

Instead of employing a single outer casing 100 10 as indicated in Figs. 1 and 2, the casing may be divided into upper and lower halves 13 and 14, as shown in Fig. 3, surrounding the side walls and top of the water jacket, respectively. Each casing may have its separate exhaust connection as indicated at 15 and 16, and an air intake opening 17 will be provided between the two parts of the casing. If desired, also the casing may be divided vertically into separate sections for 110 each cylinder as shown in Fig. 4, each separate compartment 18 having its individual exhaust connection 19.

In this design the radiating fins on the casing wall will preferably extend vertically 115 along the side walls and radially across the top, converging at the center of the cylinder head beneath the exhaust opening. The structure may obviously be otherwise modified in its details, for instance, instead of a suction-fan, a blower could be used to circulate the air through the casing.

In the foregoing description, where I have referred to the substance in the jacket as "water," I have used the word as a generic term for substances liquid at the temperature of operation of the motor and not in a limiting sense. In fact, in most instances it will be preferable to use substances of higher 125 boiling points than water, as engines operate 130

more efficiently and the combustion is more perfect at higher temperatures than can be obtained without boiling the water.

The substance in the jacket may be liquid at ordinary temperatures, such as suitable salt solutions, or glycerin, or oils of high boiling points, but I prefer to use a substance which is solid at ordinary temperatures but of low melting point so as to be liquid at the operating temperature of the engine, such for instance, as paraffin or metal alloys of low melting point.

The use of a substance of this character avoids the difficulties incidental to possible freezing of the water in cold weather, and also has the additional advantage that when the engine is cold and just being started the substance is solid and will therefore have comparatively little cooling effect, thus allowing the engine to be gotten up to normal running conditions much more rapidly than with water or other substance liquid at normal temperatures. Also the engine will keep warm a much longer time after it is stopped as the substance will solidify on the outside wall of the jacket as it cools, thereby reducing its heat absorbing capacity.

I claim:

1. In an internal combustion engine the combination of a plurality of cylinders each having a portion forming an explosion chamber, a single jacket for all said cylinders forming with the cylinder walls a fluid

tight chamber surrounding the explosion chambers, a substance in said chamber which is liquid at operating temperatures and adapted to freely circulate by convection in said chamber for transferring the heat from the cylinder walls to the outer wall of the jacket, an inclosing casing surrounding said jacket and spaced therefrom, and means for maintaining an air circulation through the casing to absorb the heat from the surface of the jacket.

2. In an internal combustion engine the combination of a plurality of cylinders each having a portion forming an explosion chamber, a single jacket for all said cylinders forming with the cylinder walls a fluid tight chamber surrounding the explosion chambers, a substance in said chamber which is liquid at operating temperatures and adapted to freely circulate by convection in said chamber for transferring the heat from the cylinder walls to the outer wall of the jacket, an inclosing casing surrounding said jacket and spaced therefrom, and means for maintaining an air circulation through the casing to absorb the heat from the surface of the jacket, said casing being divided into sections to thereby more uniformly distribute the air over the surface of the jacket to be cooled.

In testimony whereof I affix my signature.

ADOLF J. MARSCHALL.
